UNITED STATES PATENT OFFICE.

ROBERT B. WASSON, OF CRANFORD, NEW JERSEY.

HORSEPOWER-METER STAND.

Application filed November 14, 1924. Serial No. 749,897.

My invention relates to a stand for testing auto cars and more particularly to such a stand by means of which the car can be supported and tested under conditions which 5 duplicate service conditions.

One of the objects of the invention is to provide a simple, transportable testing stand carrying horizontal tracks supported above the floor level and inclined ways leading to 10 the tracks together with supporting wheels mounted in the stand and driven by the supporting wheels, in combination with load applying means for securing the auto car to the stand. The apparatus disclosed herein is 15 especially constructed for use with the engine testing apparatus of my copending application, Serial No. 681,454.

With the above and other objects in view, my invention consists in the parts, improvements and combinations more fully pointed 20 out hereinafter. Referring now to the drawings which illustrate one embodiment of the invention:

Fig. 1 is a side elevation of the stand with 25 a car diagrammatically illustrated upon it, and located in place for a test.

Fig. 2 is a plan view looking down upon the stand with the car removed.

Fig. 3 is a detailed sectional view passing 30 thru one of the supporting wheels and the brake drum, and

Fig. 4 is a side elevation of one of the supporting wheels, the brake drum and the dynamometer.

In the drawings, the stand for the auto car 35 testing device includes elevated supports which may be a pair of tracks 1, 2, which have flanged sides 3, upon which tracks and between which flanges the wheels 4, of the auto to be tested will run. These tracks 40 align the auto on the stand so that the rear wheels may take their position on the supporting wheels.

The tracks as shown are arranged horizontally 45 so as to support the car, and inclined ways 5 are provided up which the car runs on its way to the horizontal tracks. The car can thus be easily run upon the testing stand by its own power.

Means, which may be varied, are provided 50 for holding the tracks at a height above the ground. In the form of the invention illustrated, the tracks are carried in a stand formed of planks 6; cross-pieces 7, connect 55 the tracks and cross-pieces 8; connect the planks, so as to form a firm, strong stand

upon which the auto rests while being tested.

At the front, the tracks may be bent up at 9 to form a front stop for the car.

The means for supporting the tracks above 60 the ground may be varied. As illustrated, legs 10, support the front of the tracks and legs 11, support the rear ends, thus providing means for supporting the car above the ground. They also provide means for 65

mounting the supporting wheels for the car beneath the tracks, the tracks being cut out at 13, so that the rear car wheels 4, may rest upon the supporting wheels. The coaxial supporting wheels 12, are connected by a 70 shaft 14, and the shaft is mounted to rotate in bearings supported on suitable cross-members or braces 15. Means are provided for positioning and securing the auto to the tracks, with its rear wheels upon and directly above the supporting wheels. Said 75 means provide the load and permit the rear wheels to deliver their power to the supporting wheels, also permitting their free lateral oscillation. The supporting wheels are un-

grooved and provided with cylindrical faces broader than the tread of the tire so as to permit slight lateral oscillation of the rear wheels of the auto while under test. As 80 illustrated, a hook 16 pivoted at 17, to an adjusting slide 18, is provided, the slide being connected to the brace piece 20, secured to the stand. A set screw 21, cooperates 85 with the hook so as to clamp the front axle 22 of the car in place. Rear hooks 23, are 90 pivoted to the stand and are adapted to be secured around the rear axle housing 24, of the car, being provided with turnbuckles 23^a, to vary their adjustment and to vary and give the proper load and tractive effort to 95 the car. The car can thus be securely fastened in place so that it cannot move forward or backward while under test.

By providing one hook in approximately 100 the center of the front axle which receives the thrust of the two rear wheels, the propelling forces are triangulated as against a single point of restraint. This means permits the free lateral slight oscillations of the two driving wheels due to differences in friction between the driving wheels and the driven wheels, to lack of parallelism of the two rear driving wheels and other causes. This enables the two driving wheels to deliver all their power to the horse power 110 meter. The two hooks at the rear are so arranged that they do not prevent this lateral

oscillation within practical limits. Their function is to increase the pressure between the driving tires and the driven wheels. They provide the load.

5 Means, which may be varied, are provided for measuring the power given off by the rear wheels of the auto car under test. In the form of the invention illustrated, an absorption dynamometer is provided which is 10 connected to one of the supporting wheels.

As illustrated, a brake drum 25, is keyed to the shaft 14, which carries the supporting wheels 12, so as to turn with the shaft. A rope or band 26, is wound one or more times 15 about the brake pulley so as to apply the braking pressure. One end of the rope, the pulling end is connected to lever 27, of the leverage system of the dynamometer, which transmits the pull to the scale. The free end 20 of the rope is clamped upon a pulley 28, by a lever clamp 29, having a clamping pin 30. An arm 31, carrying an adjusting weight 32, is secured to the pulley 28, and turns it, so as to take up the slack in the attached end 25 of the rope. The clutch pulley 28 permits taking up the slack of the rope and also permits the angular adjustment of the weight lever, which in turn, controls its moment and pull on the rope. It thus permits an adjustment of the weight to balance the pull 30 of the motor and in this case the stand requires no attendant during the running in. A clamping arm 33, operated by handle 34, may be used to lock the rope or band while 35 adjustments are being made. When a horse-power test is being made, the weight is adjusted so as to merely take up the slack of the rope without exerting a substantial pull thereon. The weight arm may be set at an 40 angle below the horizontal and will act as a governor to control the friction of the rope on the brake pulley, being pulled towards horizontal when the friction changes.

Means are provided for measuring the pull provided by the rotating brake wheel and in the best embodiment of the invention I employ a plurality of reduction levers for transmitting the pull to the scale 35. Lever 27 is connected to the pulling end of the rope or band and at the other end of 27 is connected by link 37 to lever 36, which in turn is connected to a scale 35. Means are provided for making the reading of the dynamometer direct, i. e. so that the operator may, by multiplying the scale reading by the tachometer reading and dividing by one thousand, at once obtain the horse power that is being absorbed. As illustrated, the circumference of the brake drum is in a predetermined 50 definite relation to the reductive value of the dynamometer linkage, and is also in definite relation to the number thirty-three of the horse power dividing factor. The reductive 55 value of the linkage is one to twenty in the form shown and the circumference of the

brake drum is chosen as thirty-three feet divided by eight or four feet one and one-half inches. The scale reading of scale 35, in pounds, therefore, when multiplied by two and one-half and multiplied by the tachometer reading (giving the number of revolutions of the brake drum) and the result divided by one thousand (i. e. pointing off three decimal places) will give the horse power developed. When measuring the 75 horse power of heavy truck engines, the dynamometer leverage of twenty to one is preserved, but when measuring smaller horse power as of pleasure cars, the fulcrum of the lever 36, is moved to the right (point 38^a) 80, so as to make the reduction of the lever one to two. The reduction factor of the lever thus becomes one to eight and horse power may be read direct by merely multiplying the scale reading by the tachometer reading 85 and dividing by one thousand. Or an intermediate pivoting of lever 36 may be utilized.

A balancing weight 39, is used movable on the end of lever 36, to balance the weight of the lever 36, lever 27, and the pulling end 90 of the rope so as to bring the scale 35, to zero. A dashpot piston 40, connected to lever 36, and moving in the liquid filled dashpot 41, is connected to lever 36, by rod 42. This dampens the oscillations of the dynamometer linkage.

The brake drum is cooled to prevent charring the rope. Water is fed to the interior of the drum thru pipe 44. The water discharges from the drum thru scoop-pipe 46, 100 having a packing joint 45, with the drum, into a pail so that the flow of water may always be observed.

The tachometer 50, is preferably driven from a gear 51, which is carried by the brake shaft and intermediate gear 52, and flexible shaft 53, the tachometer giving directly the 105 number of turns per minute of the shaft 14.

Having thus described the construction, the operation of testing a car on the testing stand, will be clear. The stand may be transported and set up in a place on a level floor. The car runs up the inclined ways to the horizontal supporting tracks and is fastened down upon the stand with an adjusted load upon the rear supporting wheels. The scale is adjusted to zero by shifting the upper balance weight. The car is driven at the desired speed and the operator manipulates the weighted lever at the far end of the rope so as to take off any substantial pull on the rope. The scale gives the reading in pounds pull, at the desired speed, the speed being indicated by the tachometer.

If it is desired to run in a car, i. e. to run 125 it several hours at a fixed speed, under load, so as to note its behavior, the adjustable weight on the clutch pulley for the rope, may be set to give the necessary braking effect or load. No attendant is then needed.

Having thus described the invention, it will be understood that changes may be made in the construction for carrying the invention into effect, without departing from the principle thereof.

What I claim is:

1. An auto car testing device comprising in combination, a stand including a pair of tracks, means for supporting said tracks above the floor level and inclined ways leading to said tracks, a pair of supporting wheels mounted in said stand beneath said tracks, an absorption dynamometer carried by said stand and driven by said supporting wheels and load-applying means for securing the auto car to the stand with its rear wheels upon and above the said supporting wheels, said means being constructed to permit variation of the load applied to the supporting wheels.

2. An auto car testing device comprising in combination a support for the car, a pair of supporting wheels, an absorption dynamometer driven by said supporting wheels means for securing the front of the car to its support, and load-applying means for securing the rear of the auto car to its support the car being thus positioned, with its rear wheels upon and above the said supporting wheels, said load applying means applying the load to the supporting wheels.

3. An auto car testing device comprising in combination a stand including a pair of tracks, means for supporting said tracks above the floor level and inclined ways leading to said tracks, a pair of supporting wheels mounted in said stand beneath said tracks, an absorption dynamometer carried by said stand and driven by said supporting wheels, and three hooked members, one carried by the front of the stand and two carried by its rear portion for securing the auto to the stand with its rear wheels upon and above the said supporting wheels.

4. An auto car testing device comprising in combination, a stand including a pair of tracks, legs for supporting said tracks above the floor level and inclined ways leading to said tracks, a supporting wheel mounted in said stand beneath one of said tracks, a dynamometer driven by said supporting wheel means for securing the front of the car to the stand, and load applying means for securing the rear of the auto car to the stand, one of its rear wheels resting upon and above the said supporting wheels, said load applying means applying the load to the supporting wheel.

5. An auto car testing device comprising in combination, a stand including a pair of tracks, legs for supporting said tracks above the floor level, one pair of legs at the front and two pairs at the rear of the stand, and inclined ways leading to said tracks, a pair of supporting wheels mounted in said stand

beneath said rails and between the two pairs of rear legs, a dynamometer driven by said supporting wheels, load applying hooks pivoted to the rear of the stand for securing the auto car to the stand with its rear wheels upon and above the said supporting wheels, said hooks applying the load to the supporting wheels, and permitting lateral oscillation of the rear wheels of the car upon the supporting wheels.

6. An auto car testing device comprising in combination, a stand including a pair of tracks, means for supporting said tracks above the floor level, and inclined ways leading to said tracks, a pair of supporting wheels mounted in said stand beneath said tracks, a brake wheel driven by said supporting wheels, a flexible strap coiled about said brake wheel, means for clamping one end of said strap, a weight for pulling upon said clamping means, a dynamometer lever carried by the stand, means for securing the other end of the strap to said lever, a scale, and means for transmitting the pull of said lever exerted by the strap to said scale.

7. An auto car testing device comprising in combination a stand including a pair of tracks, means for supporting said tracks above the floor level, and inclined ways leading to said tracks, a pair of supporting wheels mounted in said stand beneath said tracks, a brake wheel driven by said supporting wheels, a flexible strap coiled about said brake wheel, means for clamping one end of said strap, a weight for pulling upon said clamping means, a dynamometer lever carried by the stand, means for securing the other end of the strap to said lever, a scale, a second lever connected to the first lever, and means for connecting said second lever to said scale.

8. An auto car testing device comprising in combination, a stand including a pair of tracks, means for supporting said tracks above the floor level and inclined ways leading to said tracks, a pair of cylindrical supporting wheels mounted in said stand beneath said tracks, a brake wheel carried by said stand and driven by said wheels, a strap coiled about said brake wheel, a scale and a reduction linkage carried by the stand, one end of the linkage being connected to said strap, the other end of the linkage being connected to said scale, the circumference of the brake drum bearing a predetermined relation to the reductive value of the said linkage.

9. An auto car testing device comprising in combination, a stand including a plurality of longitudinal planks, a pair of tracks, one arranged between each pair of planks, cross-pieces connecting the tracks and cross-pieces connecting the planks, thereby forming a stand upon which the auto car rests while being tested, inclined ways leading to said

tracks, means for supporting said stand above the floor level, a pair of cylindrical supporting wheels mounted in said stand beneath said tracks, a dynamometer driven by said supporting wheels, and load applying means for securing the auto car to the stand with its rear wheels above and upon the said supporting wheels.

- 10 10. An auto car testing device comprising in combination a stand including a pair of tracks, means for supporting said tracks above the floor level, and inclined ways leading to said tracks, a pair of cylindrical supporting wheels mounted in said stand beneath said tracks, a brake wheel driven by said supporting wheels, means for cooling the brake wheel, a flexible strap coiled about said brake wheel, means for clamping one end of said strap, a weight for pulling upon said clamping means, a dynamometer lever carried by the stand, means for securing the other end of the strap to said lever, a scale, and means for transmitting the pull of said lever exerted by the strap to said scale.
- 15 11. An auto car testing device comprising in combination, a stand including a pair of tracks, means for supporting said tracks above the floor level, and inclined ways leading to said tracks, a pair of cylindrical supporting wheels mounted in said stand beneath said tracks, an absorption dynamometer carried by said stand and driven by said supporting wheels and load-applying means for securing the auto car to the stand with its rear wheels upon and above said supporting wheels, said means applying the load to the supporting wheels.
- 20 12. An auto car testing device comprising in combination, a stand including a pair of tracks, provided with flanges, means for supporting said tracks above the floor level, and inclined ways provided with flanges, leading to said tracks, a pair of cylindrical supporting wheels mounted in said stand beneath said tracks, a brake wheel driven by said supporting wheels, means for cooling the brake wheel, a flexible strap coiled about said brake wheel, means for clamping one end of said strap, a weight for pulling upon said clamping means, a dynamometer lever carried by the stand, means for securing the other end of the strap to said lever, a scale, and means for transmitting the pull of said lever exerted by the strap to said scale.
- 25 13. An auto car testing device comprising in combination, a stand including a pair of tracks, means for supporting said tracks above the floor level, and inclined ways leading to said tracks, a pair of cylindrical supporting wheels mounted in said stand beneath said tracks, an absorption dynamometer carried by said stand and driven by said supporting wheels and load-applying means for securing the auto car to the stand with its rear wheels upon and above said supporting wheels, said means applying the load to the supporting wheels.
- 30 14. An auto car testing device comprising in combination, a stand including a pair of tracks, means for supporting said tracks above the floor level, and inclined ways leading to said tracks, a pair of cylindrical supporting wheels mounted in said stand beneath said tracks, a brake wheel driven by said supporting wheels, means for cooling the brake wheel, a flexible strap coiled about said brake wheel, means for clamping one end of said strap, a weight for pulling upon said clamping means, a dynamometer lever carried by the stand, means for securing the other end of the strap to said lever, a scale, and means for transmitting the pull of said lever exerted by the strap to said scale.

neath said tracks, a brake wheel driven by said supporting wheels, means for supplying water to the interior of and discharging it from said brake wheel so as to cool it, a flexible strap coiled about said brake wheel, means for clamping one end of said strap, a weight for pulling upon said clamping means, a dynamometer lever carried by the stand, means for securing the other end of the strap to said lever, a scale and means for transmitting the pull of said lever exerted by the strap to said scale.

15 16. An auto car testing device comprising in combination, a stand including a pair of tracks, provided with flanges, means for supporting said tracks above the floor level, and inclined ways provided with flanges, leading to said tracks, a pair of cylindrical supporting wheels mounted in said stand beneath said tracks, a brake wheel driven by said supporting wheels, means for cooling the brake wheel, a flexible strap coiled about said brake wheel, means for clamping one end of said strap, a weight for pulling upon said clamping means, a dynamometer lever carried by the stand, means for securing the other end of the strap to said lever, a scale, and means for transmitting the pull of said lever exerted by the strap to said scale.

20 17. An auto car testing device comprising in combination, a stand including a pair of tracks, provided with flanges, means for supporting said tracks above the floor level, and inclined ways provided with flanges, leading to said tracks, a pair of cylindrical supporting wheels mounted in said stand beneath said tracks, an absorption dynamometer carried by said stand and driven by said supporting wheels and load-applying means for securing the auto car to the stand with its rear wheels upon and above said supporting wheels, said means applying the load to the supporting wheels.

25 18. An auto car testing device comprising in combination, a stand including a pair of tracks, provided with flanges, means for supporting said tracks above the floor level, and inclined ways provided with flanges, leading to said tracks, a pair of cylindrical supporting wheels mounted in said stand beneath said tracks, a brake wheel driven by said supporting wheels, means for cooling the brake wheel, a flexible strap coiled about said brake wheel, means for clamping one end of said strap, a weight for pulling upon said clamping means, a dynamometer lever carried by the stand, means for securing the other end of the strap to said lever, a scale, and means for transmitting the pull of said lever exerted by the strap to said scale.

30 19. An auto car testing device comprising in combination, a stand including a pair of tracks, provided with flanges, means for supporting said tracks above the floor level, and inclined ways provided with flanges, leading to said tracks, a pair of cylindrical supporting wheels mounted in said stand beneath said tracks, an absorption dynamometer carried by said stand and driven by said supporting wheels and load-applying means for securing the auto car to the stand with its rear wheels upon and above said supporting wheels, said means applying the load to the supporting wheels.

In witness whereof, I have signed my name to this specification.

ROBERT B. WASSON.
